UNITED STATES PATENT OFFICE.

HERMAN PLAUT, OF NEW YORK, N. Y.

DESIGN FOR AN ELECTROLIER.

45,020.

Specification for Design.

Patented Dec. 9, 1913.

Application filed September 18, 1913. Serial No. 790,544. Term of patent 7 years.

To all whom it may concern:

Be it known that I, HERMAN PLAUT, a citizen of the United States, and a resident of the borough of Manhattan, city, county, and State of New York, have invented a new, original, and ornamental Design for an Electrolier, of which the following is a specification, reference being had to the accompanying drawing, forming a part hereof, which shows the design in perspective.

The design comprises a substantially hemispherical body portion, having an ornamented rim, below which is an ornamentation consisting of a draped scarf and foli-

ated knots, the bottom of the body having a radiating shell-like ornamentation and a centrally located depending tip. The body is supported by curved arms from a centrally located substantially hemispherical plaque.

I claim:

The ornamental design for an electrolier, substantially as shown and described.

HERMAN PLAUT.
